MIRROR GALVANOMETER

Siegfried Götze and Wilhelm Fritsch, Frankfurt am Main, Germany, assignors to Hartmann & Braun Aktiengesellschaft, Frankfurt am Main, Germany

Filed Feb. 26, 1959, Ser. No. 795,815

Claims priority, application Germany Mar. 6, 1958
2 Claims. (Cl. 324—154)

The invention relates to a mirror galvanometer used for rapid current changes. The object of the invention is to provide a rigid connection between the measuring coil and the mirror even if the latter is arranged above the coil and in a known manner with the shaft of the system consisting of the coil and mirror passing the center of mass of the mirror. Furthermore the invention solves the problem of keeping the moment of inertia of the oscillating system as small as possible for enabling a maximum inherent frequency for a given directive force.

The invention is set forth in the drawing wherein:

FIG. 1 is a longitudinal sectional view of the coil and mirror and mounting means therefor;

FIGS. 2 and 3 are enlarged side and front views respectively of the coil and mirror system;

FIG. 4 is a transverse sectional view of the invention, the section being taken along the line 4—4 of FIG. 1 looking in the direction of the arrows of said line; and

FIGS. 5 and 6 are transverse sectional views taken along the respective lines 5—5 and 6—6 looking in the direction of the arrows of said lines.

In the drawing a hollow mount M having upper and lower portions P and P' carries the essential components of the invention.

The system consisting of a coil 1 and mirror 2 is suspended between strips 3, 3' which are fastened to springs 4. The tension of strips 3, 3' for torsional stress can be adjusted by means of screw 5 arranged in the threaded nut member 8. Longitudinal displacement of the nut member 8 is possible, however it cannot be rotated between the two jaws 9 on the upper portion. The nut member 8 is secured by a screw 7 after having its position adjusted for tension of the stress. The head of screw 5 rests on the upper edge of jaw 9. Coil 1 is arranged in the field of a permanent magnet (not shown) acting on pole pieces 10 and 11. The mount has a window 12 for the light beam to be deflected by mirror 2.

Four thin and rather stiff wires or filaments 13, 14, 15, 16 of elastic material such as metal glass or quartz, which can be bent to the shown configuration are glued or fixed in some other way to the flange surface of coil 1.

At each flange side the wires should be arranged far apart; as shown by FIGS. 2 and 6 they are approximately in the center of the vertical parts of the coil flanges. Each two opposite pairs of wire (13, 14 and 15, 16 in the drawing) are fixed just above the coil at a narrow side of the mirror, e.g. also by gluing or cementing, the wires of each pair fitting tightly to each other. Above the mirror

2

all the four wires are combined in socket 17 and below the moving coil in socket 18. The sockets are again fixed to strips 3, 3', e.g. glued on.

Current supply is via strips 3, 3' which for this purpose are extended beyond sockets 17 and 18 and which at 19 and 20 are soldered to the ends of the moving coil as at S. If the wires are of metal the cement or adhesive may be of insulating material to prevent short circuiting of the coil. Of course metal wires could be discontinued at the zone of the mirror or coil.

Instead of fastening the pairs of wire 13, 14 and 15, 16 to the two narrow sides of the mirror as shown in the drawing it is also possible to fasten wires 13, 15 and 14, 16 to the mirror. In this case only the position of 15 the reflector surface to the coil winding axis changes.

A coil-mirror system as covered by the invention is fitted with an extremely rigid and safe connection between the coil and the mirror. Moreover, the moment of inertia of the whole system referred to the axis of oscillation, mainly determined by the coil and the mirror as well as the thin wires, will hardly be increased.

The invention claimed is:

1. A galvanometer comprising a pair of substantially longitudinally aligned tension strips having inner end 25 portions respectively projecting toward each other, and means for mounting the strips, magnet pole pieces in the zone between the strips, a coil to turn about axis substantially in line with the strips and between the pole pieces and having exterior frontal faces extending substantially 30 in a direction common with that of the strips, a flat rectangular mirror situated between the coil and one of the strips, and spaced from the coil, and two pairs of wire-like members substantially extending from one strip to the other and adhered together and secured thereto at 35 their respective end portions, each pair of said members being respectively secured on one of said frontal faces and on said mirror at opposite edge portions thereof, the four members being spaced from each other in the zone between coil and the mirror to form a substantially rigid connection between the coil and mirror for substantially quantitative transmission of turning motion from the coil to the mirror when the portions of said members between the coil and mirror are under tension from said strips.

- 45 2. A galvanometer as claimed in claim 1, the members, coil and mirror being substantially symmetrical about said axis.
